UNITED STATES PATENT OFFICE.

MICHAEL W. MAHAR, OF NATIONAL MILITARY HOME, MONTGOMERY COUNTY,
ASSIGNOR OF ONE-THIRD TO PHILLIPP MITCHELL, OF DAYTON, OHIO.

POCKET-BOOK HOLDER.

SPECIFICATION forming part of Letters Patent No. 281,638, dated July 17, 1883.

Application filed April 5, 1883. (No model.)

To all whom it may concern:

Be it known that I, MICHAEL W. MAHAR, of National Military Home, in the county of Montgomery and State of Ohio, have invented 5 certain new and useful Improvements in Pocket-Book Holders; and I do hereby declare that the following is a full, clear, and exact description of the invention, which will enable others skilled in the art to which it appertains to 10 make and use the same, reference being had to the accompanying drawings, which form a part of this specification, and in which—

Figure 1 is a perspective view of my improved pocket-book holder without the pocket-book. Fig. 2 is a similar view, showing it as 15 applied to a pocket-book; and Fig. 3 is a perspective view, showing the pocket-book in section, for the purpose of illustrating a different means of fastening the pocket-book to the 20 holder.

Similar letters of reference indicate corresponding parts in all the figures.

My invention has relation to that class of devices which are intended to fasten a pocket-book or wallet securely to the hand of a person; and it consists in the detailed construction 25 of a pocket-book holder, as hereinafter more fully described, and particularly pointed out in the claims.

In the accompanying drawings, A represents 30 the body of my improved holder, which is made of leather or other suitable material, and provided with cross-pieces B C at opposite ends. Stitched upon these cross-pieces are straps 35 (shown at D and E) of elastic webbing, one of which is provided with buckles F and G, or equivalent fastening devices, for connecting its free ends. Upon the cross-piece B is fastened a piece of metal, H, the ends of which 40 are bent upwardly and notched, so as to form projecting teeth or points h.

The pocket-book is fastened to the holder by making small slits in the back and inserting the points h through the same, after which they are

clinched down on the inside of the book. If 45 desired, however, the fastening device shown in Fig. 3 may be employed, which consists of a screw, the head of which is fastened midway upon the cross-piece B, and the point of which is inserted through the back of the pocket-book by piercing the same, after which a flat head or nut, K, is screwed upon screw I and tightened down, so as to hold the book firmly in position. By simply unscrewing the flat nut or head K the pocket-book and its holder 55 may readily be detached.

To use the holder one of the elastic straps, E, is buckled around the wrist and the other is slipped across the back of the hand, between the thumb and forefinger. If desired, the 60 buckles or fastening devices F G may be made adjustable upon their respective ends of the strap, so as to adjust it to different-size hands.

Having thus described my invention, I claim and desire to secure by Letters Patent of the 65 United States—

1. The pocket-book holder consisting of the flexible body A, having cross-pieces B C, elastic straps D and E, having the fastening devices F G, and a suitably-constructed catch 70 for fastening the pocket-book permanently upon the holder, substantially as and for the purpose shown and set forth.

2. The pocket-book holder consisting of the flexible body A, having cross-pieces B C, elastic straps D and E, having the fastening devices F G, and the fastening device consisting of the pointed screw I and flat nut K, whereby the pocket-book may be fastened detachably to the holder, substantially as and for the purpose shown and set forth.

In testimony that I claim the foregoing as my own I have hereunto affixed my signature in presence of two witnesses.

MICHAEL W. MAHAR.
